[57] CLAIM

The ornamental design for a coin bank, as shown and described.

DESCRIPTION

FIG. 1 is a side elevational view of a coin bank showing my new design, the side opposite being substantially a mirror image;

FIG. 2 is a rear elevational view thereof;

FIG. 3 is a top plan view thereof;

FIG. 4 is a front elevational view thereof;

FIG. 5 is a cross-sectional view thereof taken along line

5—5 of FIG. 4; and

FIG. 6 is a bottom plan view thereof.
